UNITED STATES PATENT OFFICE

HELEN MARIE WEBER, OF STEVENS POINT, WISCONSIN

DESIGN FOR AN ARTIFICIAL BAIT OR SIMILAR ARTICLE

Application filed May 10, 1932. Serial No. 43,768. Term of patent 3½ years.

To all whom it may concern:

Be it known that I, HELEN MARIE WEBER, a citizen of the United States, residing at Stevens Point, in the county of Portage and State of Wisconsin, have invented a new, original and ornamental Design for an Artificial Bait or Similar Article, of which the following is a specification, reference being had to the accompanying drawing, forming part thereof.

Fig. 1 is a top plan view,

Fig. 2 is a side view, and

Fig. 3 is a bottom view of an artificial bait or similar article showing my new design.

I claim:

The ornamental design for an artificial bait or similar article, as shown.

HELEN MARIE WEBER.
